RATCHET MECHANISM FOR WRENCHES

Filed March 14, 1946

UNITED STATES PATENT OFFICE

2,507,681

RATCHET MECHANISM FOR WRENCHES

Edwin R. Sage, Los Angeles, Calif.

Application March 14, 1946, Serial No. 654,258

5 Claims. (Cl. 74—157)

1

This invention relates to improvements in ratchet mechanism for wrenches.

The main objects of this invention are:

First, to provide a ratchet wrench having two methods of operation, namely, means for rapidly adjusting the nut or screw through its freely movable stage without rotating the wrench and a ratchet action of the type in which the wrench is actuated in the regular manner.

Second, to provide a reversible ratchet wrench embodying means for rapidly running up the nut or screw for final setting and the reverse action.

Third, to provide a wrench structure embodying these features which is quite compact and is strong and durable.

Fourth, to provide a reversible ratchet wrench which is very convenient to reverse and to operate.

Objects relating to details and economies of the invention will definitely appear from the description to follow. The invention is defined in the claims.

A structure which embodies the features of the invention is clearly illustrated in the accompanying drawing, in which:

Fig. 1 is a plan view of a wrench embodying the invention.

Fig. 2 is a view mainly in longitudinal section on line 2—2 of Fig. 1.

Fig. 3 is a plan view with the handle removed and the top plate or chamber cover removed.

Fig. 4 is a fragmentary view mainly in section on line 4—4 of Fig. 2 showing details of the holding ratchet and coacting dogs.

The embodiment of the invention illustrated comprises a chambered body portion 1 having a side opening 2 facilitating the insertion and removal of parts, the opening being provided with a closure plate 3 secured by means of the screws 4. The handle 5 is tubular or hollow and has threaded engagement with the body portion as shown at 6. The spindle 7 is journaled in the front wall 8 of the body portion and in the plate 3, the spindle having a tang 9 adapted to engage a socket or other tool driven by the wrench. The spindle is provided with a toothed holding ratchet wheel 10 and with a pair of driving ratchet wheels 11 and 12. All three of these parts are keyed or fixed to the spindle, the keys or splines not being illustrated.

I provide a pair of holding dogs 13 which are pivotally supported at 14 in a wall of the recess 15 receiving the holding ratchet wheel and these dogs. The dogs are urged into engagement with the holding ratchet by means of the springs 16 55

2

seated in the wall of the recess. It will be noted that one dog is associated with the holding ratchet wheel to hold the spindle against rotation in one direction and the other to hold the spindle against rotation in the opposite direction, the dogs ratcheting over the teeth of the ratchet as the holding ratchet wheel is actuated.

I provide a pair of driving pawls 17 of the rack type, one driving pawl coacting with one of the 10 driving ratchet wheels and the other pawl coacting with the other driving ratchet wheel. These actuating pawls are driven from a common actuating member 18 which is in the form of a rack reciprocatingly mounted in the stem portion 19 15 of the body member of the wrench. The stem portion 19 is provided with a stepped bore 20 to receive this member.

The coiled spring 21 is arranged on the stem 22 of the rack in thrust engagement with the 20 washer 23 seated against the shoulder 24 and engaging the washer 25 on the stem, this acting to return the actuating member. The pawls 17 are pivoted at 26 to this rack actuating member and are urged to engaging position by the spring 25 27 extending between the pawls. The spring 27 acts to bias both pawls to ratchet wheel engaging position. The lever 28 is pivoted at 29 between the ears 30 extending from the wrench body, the lever being provided with a toothed segment 31 coacting with the rack. The lever is positioned to be grasped and actuated by the hand of the operator grasping the wrench, and is positioned to be conveniently engaged by the index finger of the user grasping the wrench and holding it in engagement with the work.

Means are provided for selectively holding one of the pawls and one of the holding dogs out of operative position while the other pawl and dog are in operative position. The means illustrated 40 consists of the cams 32 and 33 which are provided with a common pivot 133 engaging the front wall of the wrench and the closure plate thereof as shown in Fig. 2. The cam is adapted to hold one of the pawls and one of the locking dogs in 45 inoperative position as shown in Fig. 3. For convenience in manipulation the pivot 133 is provided with an arm 34 on the outer side of the closure plate 3, the arm having a finger piece 35.

With the parts thus arranged the work such 50 as a nut or screw may be rapidly turned up through its easily turned movement to setting position after which the wrench is manipulated by means of the handle to firmly set the work. The reverse action may be had when the parts of the wrench are in reversing position, the work

being loosened by means of the lever. The pawls are effective for both manipulations.

I have illustrated and described the invention in a highly practical embodiment thereof. I have not attempted to illustrate or describe other embodiments and adaptations which I contemplate as it is believed this disclosure will enable those skilled in the art to adapt the invention as may be desired.

Having thus described my invention, what I claim as new and desire to secure by Letters Patent is:

1. In a wrench, the combination of a chambered body provided with a handle, a spindle disposed transversely of the handle and provided with a holding ratchet wheel and a pair of driving ratchet wheels, said wheels being fixed to said spindle, a pair of spring biased holding dogs operatively associated with the holding ratchet wheel with one acting to hold the spindle against rotation in one direction and the other against rotation in the opposite direction, an actuating rack reciprocatingly mounted within said body and provided with a return spring, a pivoted actuating lever positioned to be actuated with the hand supporting the wrench and provided with a segment coacting with said actuating rack, the return spring of the rack acting to return the lever to its initial position, a rack pawl for each driving ratchet wheel pivotally mounted on said actuating rack, the pawls engaging their respective coacting ratchet wheels on opposite sides of their axis, a spring common to both of said pawls for urging them into engaging position, and cams mounted between said rack pawls and holding dogs adapted to selectively hold one rack pawl and one dog in inoperative position while permitting the other rack pawl and other dog to coact with said ratchet wheels, said cams being provided with a finger-piece on the outside of the wrench body.

2. In a wrench, the combination of a chambered body provided with a handle, a spindle disposed transversely of the body and provided with a pair of driving ratchet wheels, a pair of holding dogs operatively associated with the spindle with one acting to hold the spindle against rotation in one direction and the other against rotation in the opposite direction, an actuating rack reciprocatingly mounted within said body and provided with a return spring, a pivoted actuating lever positioned to be actuated with the hand supporting the wrench and provided with a segment coacting with said actuating rack, a rack pawl for each driving ratchet wheel pivotally mounted on said actuating rack, the pawls being spring biased and engaging their respective coacting ratchet wheels on opposite sides of their axis, and means for holding one of said pawls and one of said locking dogs in inoperative position while permitting the other to coact with its ratchet wheel and said spindle respectively.

3. In a wrench, the combination of a chambered body provided with a handle, a spindle disposed transversely of the body and provided with a holding ratchet wheel and a pair of driving ratchet wheels, spring biased holding dogs operatively associated with said holding ratchet wheel, an actuating member, an actuating means operatively associated with said member and positioned to be actuated from within the body, a rack pawl for each of said driving ratchet wheels operatively connected with said actuating member, and means for selectively holding one of said rack pawls and locking dogs in inoperative position while the other of said pawls and dogs are in operative position.

4. In a wrench, the combination of a chambered body provided with a handle, a spindle, a pair of oppositely acting rack and ratchet means for rotatably driving said spindle in opposite directions, common means for actuating said rack and ratchet means comprising a reciprocatingly mounted rack member provided with a return spring and an actuating lever provided with a segment coacting with said rack member, the lever being positioned to be actuated with the hand supporting the wrench, a pair of oppositely acting holding dogs for said spindle each acting to hold the spindle against rotation in one direction while permitting rotation in the opposite direction, and means for adjusting said racks and locking dogs to hold a selected one of each of said racks and dogs in inoperative position.

5. In a wrench, the combination of a chambered body provided with a handle, a spindle, a pair of pawl and ratchet means for driving said spindle in opposite directions, a pair of oppositely acting holding dogs for said spindle each acting to hold the spindle against rotation in one direction while permitting rotation in the opposite direction, a pawl actuating member operatively associated with both of the pawls of said pawl and ratchet means, means for actuating said actuating member independently of the oscillation of the wrench by its handle, and means for adjusting said ratchet pawls and holding dogs to selectively hold one of each of said pawls and dogs in inoperative position.
